UNITED STATES PATENT OFFICE.

WALTER JACOB WOHLENBERG, OF NORMAN, OKLAHOMA.

CONSTRUCTION FOR ROTARY ENERGY-TRANSFORMERS.

1,162,839.

Specification of Letters Patent.

Patented Dec. 7, 1915.

Application filed December 12, 1914. Serial No. 876,962.

To all whom it may concern:

Be it known that I, WALTER JACOB WOHLENBERG, a citizen of the United States, and a resident of Norman, in the county of Cleveland and State of Oklahoma, have invented a new and Improved Construction for Rotary Energy-Transformers, of which the following is a full, clear, and exact description.

10 My invention relates to energy transformers in which work is transformed into some form of energy by means of the forced relative motion between the parts of said transformers.

15 An object of my invention is to have the stator of the energy transformer centrally located within the rotor so that if desired, the rotor may be driven by applying a tangential force to its periphery from an external source of power, instead of by the main shaft.

20 A further object is to have the main gear of a reduction gear, through which the transformer may be driven, directly attachable to the rotor of the transformer, thus eliminating the otherwise necessity of extra housing and bearings for the main gears of the reduction gear.

25 Another object of my invention is to have in fluid rotary energy transformers (such as pumps) such a fluid path that only one outside packing box is necessary and this may be either at the discharge or inlet of said pumps.

30 Another object of my invention is to have the means whereby in multi-stage centrifugal pumps, only one packing box is necessary.

35 I accomplish these and other objects of my invention by the structures disclosed in the accompanying drawing and in which invention, the same characters of reference indicate corresponding parts in all the views shown.

40 Figure 1 is a side view of a general application of my principle of construction to any energy transformer. Fig. 2 is another view of the general application shown in Fig. 1. Fig. 1 being a view of Fig. 2 from line L—L 45 looking in direction of arrows. Fig. 3 shows a reduced end view of the rotor portion of the transformer shown in Fig. 2 to show how the supporting webs 2 are attached. Fig. 4 is a cross sectional view of a centrifugal pump in which the principle is applied and Fig. 5 is a reduced view of Fig. 4 looking from line z—z in direction of arrows.

Referring first to Figs. 1 and 2, B is a base which supports by column b_1 , the stator S of the transformer centrally within the rotor 60 R. The rotor shaft r_3 fits in the bearing b_3 supported by column b_2 . The shaft r_3 also fits snugly into the central portion of the web construction r_2 , shown in Fig. 3 which in turn is fastened to the rotor. The rotor 65 is thus suspended about the stator S so that it has running clearance C.

The rotor R may be driven either by the central shaft r_3 or by the application of tangential force at an external circumference 70 which circumference may be the periphery. In the latter case either a belt or chain might be used as shown by D'—D' or the periphery might have a gear r_1 surrounding and attached to it which might be driven by a 75 pinion D through drive shaft d. The pinion being supported in bearings b_5 of columns b_4 .

Referring now to Figs. 4 and 5 we have again a base B supporting a centrally located stator S by means of column b_1 and 80 the rotor suspended about it with running clearance C by means of main or central shaft r_3 through bearing b_3 supported on column b_2 . In this case the rotor may also have a bearing support in the stuffing box g 85 and between stages at h where a ring might be fastened to the tips of the stationary blades f.

As before the rotor might be driven from the central or main shaft r_3 or by the application of tangential force to its periphery as shown by F in Fig. 5.

In Fig. 4, i is the fluid inlet. The stuffing box g will be suitably packed so that the fluid will pass from i into the pump 90 proper with reduced leakage. As shown here the fluid path is from i to 1, 2, 3, and 4 where one stage or cycle has been completed. From here the fluid passes through the second stage starting at 1 and then passing to 1, 2, 3, and 4 and so on to the outlet. In this representation the blades e are fastened to the rotor R and the blades f to the stator S. Hence the blades e rotate giving the fluid an accelerating motion as it passes from 1 to 1. 2. At 2 the fluid has reached its maximum velocity and due to the increase of cross section from 3 to 4, the kinetic energy given to the fluid between 1 and 2 is converted by means of stationary blades f to potential energy or pressure in the fluid as it passes from 3 to 4. From 1 to 2 the cross section of course decreases.

As here shown the stuffing box g is at the

inlet. By taking blades *f* from stator and fastening to rotor and by taking blades *e* from rotor and fastening to stator the fluid path will be just reversed so that now *n* is 5 the inlet and *i* the outlet when *g* becomes the stuffing box at discharge.

It should now be clearly understood that this invention is not concerned with cross sectional variations of passages 1—2—3—4 10 or with the curvature of the blades *e* and *f*, but has for its foundation the centrally located stator whereby means are afforded 1st, for driving the rotor directly by the application of a tangentially applied force 15 from an external source of power, and 2nd, for having fluid inlet and discharge passages, in the energy transformers having fluids as energy storing mediums, with axes coincident with that of rotor and extending 20 from and to the same end of rotor whereby only one stuffing box is used.

Obviously many changes might be made in the details of construction or in the combination of the unit parts of the construction 25 without departing from the spirit and scope of this invention. For instance, the unit parts might be so arranged as to balance end thrust by having rotors with thrust surfaces opposed. I do not, therefore, wish 30 to limit my invention to the exact construction or combination of parts shown.

Having described my invention, I claim as new and desire to secure by Letters Patent:

35 1. The combination in rotary energy transformers of a stator with a rotor, the stator centrally located within the rotor, the inlet and outlet fluid passages having an axis coincident with that of rotor, said 40 passages being concentrically located with respect to each other and extending from and to the same end of the rotor whereby one packing gland only is necessary.

2. The combination in multi-stage rotary 45 energy transformers of a stator with a rotor, the stator centrally located within the rotor, the inlet and outlet fluid passages having an axis coincident with that of rotor and said passages being concentrically 50 located with respect to each other and extending from and to the same end of the rotor whereby one packing gland only is necessary.

3. The combination in rotary energy 55 transformers of a stator with a rotor, the stator centrally located within the rotor, the inlet and discharge fluid passages having an axis coincident with that of rotor, said passages being concentrically located one with 60 respect to the other and extending from and to the same end of the rotor whereby only one packing gland is used, the rotor having means whereby it is driven by the

application of a mechanical force from an external source of power, said force being 65 tangentially applied to an external circumference of the rotor.

4. The combination in rotary energy 70 transformers of a stator with a rotor, the stator centrally located within the rotor, the inlet and discharge fluid passages having an axis coincident with that of the rotor said 75 passages being concentrically located one with respect to the other and extending from and to the same end of the rotor whereby only one packing gland is necessary, together with reduction gear comprising a pinion driven main gear directly attached to an external circumference of the rotor.

5. The combination in rotary energy 80 85 transformers of a stator with a rotor, the stator centrally located within the rotor, inlet and outlet fluid passages having axes coincident with that of the rotor, and being concentrically located one with respect to another, whereby it is necessary to have packing at only one end of said passages.

6. The combination in multi-stage rotary 90 energy transformers of a stator with a rotor, the stator centrally located within the rotor, the inlet and outlet fluid passages having axes coincident with that of the rotor and being 95 concentrically located one with respect to another, whereby it is necessary to have packing at only one end of said passages.

7. The combination in rotary energy 100 105 transformers of a stator with a rotor, the stator centrally located within the rotor, the inlet and discharge fluid passages having axes coincident with that of the rotor and being concentrically located one with respect to another, whereby it is necessary to have packing at only one end of said passages; the rotor having means whereby it is driven by the application of a mechanical force from an external source of power, said force being tangentially applied to an 110 external circumference of the rotor.

8. The combination in rotary energy 110 115 transformers of a stator with a rotor, the stator centrally located within the rotor, the inlet and discharge fluid passages having axes coincident with that of the rotor and being concentrically located one with respect to another, whereby it is necessary to have packing at only one end of said passages; together with reduction gear comprising a pinion driven main gear directly attached to an external circumference of the rotor.

120 In testimony whereof, I have signed my name to this specification in the presence of two subscribing witnesses.

WALTER JACOB WOHLENBERG.
